claims on an apparatus designed to manufacture garlands of many varieties from materials that may be used as straight cord or by themselves. This invention will cover the apparatus or machines used in making the so-called "corded" garlands which are the garlands that are

so often seen before, at exhibitions, advertising, etc., and also the so-called "bouquets" which are garlands

UNITED STATES PATENT OFFICE

APPARATUS FOR MAKING WREATHS

Application April 7, 1932. Serial No. 603,759

10 Claims.

This invention relates to an improved apparatus for making garlands such as Christmas wreaths, and also for making what is called "roping." The latter is made up of the same kinds of material as wreaths but instead of being arranged in circular form, it is in rope-like form, such as used for festooning.

The idea of my invention is to provide a working apparatus to supplement the work of the skilled operator and to thereby greatly increase his output. The operator selects the materials and varies their arrangement at his pleasure. The division of labor is between the operator, who has a chance to contribute all his personal skill in the various arrangements of flowers, leaves, and stems, and the machine, which is operable to speed up the work when it does not interfere with the operator's hand work that is to give quality to the finished product.

20 The apparatus specially arranged for this purpose is shown in the accompanying drawings, in which—

Fig. 1 is a side elevation of the apparatus;

Fig. 2 is a top view with part of the driving

25 belt cut away;

Fig. 3 is a sectional view taken through the machine on the line indicated at 3—3 of Fig. 4;

Fig. 4 is a detail sectional view on line 4—4

30 of Fig. 1; and Fig. 5 is a detail view.

As shown, the apparatus is made up of a frame

1 having a flat top portion like a work bench. The pivoted foot treadle 2 is mounted to turn crank 3 and through the pulley and belt shown

35 to drive shaft 4 on the top of the bench. The latter may instead be driven by an electric motor but there is an advantage in the operator himself driving the apparatus, as will be pointed out.

At the other end of the bench from shaft 4 a

40 rotatable shuttle wheel 5 is mounted. This shuttle is of light weight and, as shown, is made of wood, in annular shape, with its inner periphery supported on an arch-shaped metal piece 6 extending upwardly through an opening in the

45 bench. The shuttle support 6 is supported at the bottom of the bench by being fastened to a metal strap 7 (Fig. 3) which being bolted to the bench, has an end projecting from the bottom side of

the opening for the shuttle and is there fastened

50 to strap 6 on its inner periphery. This leaves the strap free on its outer periphery to receive,

support, and guide the shuttle 5. At the top of strap 6 there is a C-shaped guide 8 (see Fig. 3)

55 to extend up and adjacent one side of the shuttle,

over the top, and down the opposite side a suffi-

cient amount to receive the shuttle 5 and

keep it from moving sideways. The shuttle 5 is

driven by a pulley 9 and belt 10 which is

driven by a pulley 11 and belt 12 which is

driven by a pulley 13 and belt 14 which is

driven by a pulley 375 and belt 376 which is

driven by a pulley

wire support for a wreath or a portion of an indefinite length of wire for a "roping") in position for the workman to place flowers or leaves around it and for the shuttle's operation in binding them to the wire for support) I provide a pair of elevated abutments 51 and 52, see Fig. 3. These abutments are located on opposite sides of the opening through the bench provided for the string or wire from spool 21 to pass through 10 as it travels with the shuttle to wind over the supporting wire that carries the leaves or flowers. Abutment 51 is preferably located in the plane of the shuttle 5. Abutment 52 is spaced a short distance toward the treadle side of the bench 15 where the workman stands. The idea is to have the abutments positioned so the workman can place the stems of the leaves and flowers to rest on abutment 51 with the foliage supported by abutment 52 and a short length of stem between 20 abutment 51 and the plane of the binding wire's rotation as it feeds from the spool to bind the stems. In Fig. 4 I have shown (in dotted line) a wire positioned in the apparatus for making a wreath. The hook 90 may be turned into position to hold the outer end of the wire core from 25 getting out of place during winding. The spaced supports 53, 54, and 55 are arranged with abutments 51 and 52 to normally support a garland or wreath in the making while in horizontal position. From such position the workman can 30 lift it and tip it and move it around by hand as will be pointed out. All these supports including the abutments 51 and 52 space the wreath well above the bench so the workman may get at 35 all sides of the core in building the wreath.

In Fig. 1 I have indicated a pivoted knife 60 normally held up by a spring. The operator uses this as a convenient chopper, to cut off the stems of his flowers or foliage so as to fit them 40 for placing and spacing on the core wire, with the stem ends resting on abutment 51 and with the foliage the proper distance with respect to the winding plane. Both abutments 51 and 52 have their opposing faces curved (see Figs. 2 and 45 3) so as to guide the binding string without catching and at the same time to leave hand space for the workman to apply the flower building material from the sides and underneath.

The wire core 71 for making "roping" is carried 50 on a supply spool 70 mounted on the shelf 11 under the bench (see Fig. 1). Its end may be kept ready at hand by being pinched in a bench hole by plug 73 (Fig. 3) in line with abutments 51 and 52.

55 Whether a circular core wire 30 for a wreath or a straight core wire 71 is used in the apparatus, such wire is arranged to be conveniently moved step by step and by hand across the space between abutments 51 and 52 where the application of the foliage to the core is made by the workman and where the binding thread or wire is wound on by the rotatable shuttle. The position of the skilled workman is where he can operate the pivoted treadle 2, pick up foliage from 60 a supply arranged in bunches on a convenient belt conveyor 91 (shown partially in Fig. 2) by unskilled workmen. The skilled workman applies the foliage to the core wire in the apparatus and operates the treadle to turn the shuttle and 65 thus bind the foliage stems on the core wire.

70 The spirit of the apparatus disclosed is to so arrange the parts that the operator can control the quality of the product. The foliage is not a raw material of uniform nature, but of constantly varying kind. On this account the

skilled operator is highly desirable so as to make the most of his available raw material and to have his artistic skill evidenced in the finished product by the most appropriate arrangement of the foliage (of flowers and/or leaves, berries, etc.). 80

The particular apparatus is useful not only to speed up the skilled operator's work but in the following more important ways with regard to retaining the quality of the skilled operator's work. The arrangement of abutments 51 and 52 with relation to the core wire is such that the operator can arrange the foliage by hand exactly where it will be most appropriately positioned on the core wire. The binding wire is conveniently rotatable around the core wire exactly where the operator determines it can be best applied. This is determined by the hand placement of the core wire in its step-by-step movements relative to the winding plane. The operator can work with his hands on both sides and from the top or bottom of the core wire. Sometimes he wants to turn the binding wire on rapidly and sometimes slowly, sometimes with more or less tension, sometimes with more or 90 less pitch between the turns. He applies the foliage according to the skill of his hand arrangement. He operates the apparatus by foot power or he can turn the shuttle very slowly by hand, which is sometimes desirable, and at all 100 times he sees and controls the arrangement of the foliage as it is bound into permanent relation to the core wire.

There is an advantage in mounting the shuttle on the arc-shaped strap 6, as described. It is 110 not desirable to rotate the shuttle rapidly and continuously because that would not give the operator a chance to build the foliage on the core to the best advantage. Preferably the shuttle is operated intermittently and it is desired 115 to avoid such a momentum in the movement that would make it difficult to stop it for the progressive steps in the arrangement of the foliage with respect to the core and binding wire. By building the shuttle of light weight construction 120 such as wood and having it mounted for support and for frictional contact with the strap 6 and rather loosely mounted thereon, the operator can easily stop the winding wire's rotation at any point desired and easily start it up again. 125 Fig. 5 shows where it has been stopped for the shuttle gate to be opened, a finished wreath to be removed and a new circular core wire to be inserted.

One feature of the apparatus is that it is constructed with the idea of the workman's operation by hand or foot to the end that better work can be accomplished. The apparatus is designed to assist the workman in those steps which can be more conveniently carried out as a mere 130 mechanical operation and to enable the workman to apply practically all his time and skill in directing the quality of the work. The result is that much better work is obtained by the use of the apparatus than can be obtained 140 by a power driven automatic machine where the workman is only a machine tender and much more work of the desired high quality can be obtained than if a skilled workman did not have the machine to speed up his personal skill. 145

Apparatus of the character described is usually and best used in the country districts where the raw material is plentiful. The product is a seasonal one and is ordinarily made up by the country people, many of whom have ac- 150

quired real skill in their hand work. During most of the year they work at other tasks but around Christmas time concentrate on wreaths and roping. These people are not ordinarily available for factory work. They are handicraft workers. My apparatus is planned as an inexpensive work bench having particular combinations of elements for operation by such workers during their rush season. It can be set up anywhere and gives the handicraft worker who uses one a great advantage in the particular trade for which it is designed.

Having described the apparatus in its preferred form I claim as my invention:

1. In an apparatus having a belt-driven rotatable annular shuttle carrying a spool for winding thread to bind foliage on a wire core, the combination of an arc-shaped member in constant frictional contact with the interior periphery of the shuttle and spaced abutments to support a core wire and foliage in horizontal position for the binding operation, said abutments being so shaped as to permit the hand arrangement of the foliage on all sides of the core wire both during and between rotatable movements of the shuttle.

2. The combination set forth in claim 1 in which said abutments are spaced substantially equal distances in opposite directions from the winding plane of the binding thread as it is applied to the core.

3. The combination set forth in claim 1 and belt means to drive the shuttle, said shuttle having a gate operable to open between the flights of said belt, and a support also located between the flights of the belt for maintaining an annular core wire when resting on said abutments in horizontal position.

4. The combination in a foliage wrapping apparatus a workman's bench, an opening therein, a support extending from the under side of said opening, an arc-shaped member on said support, an annular shuttle rotatably mounted on said member with its axis spaced above the work bench, spaced abutments on opposite sides of said opening to horizontally support a core wire extending through said axis whereby the workman at the bench may arrange foliage on all sides of the wire and in wrapping relation to the shuttle's rotation and means operable by the workman at the bench to rotate said shuttle for the wrapping operation.

5. The combination in a wreath making apparatus a workman's bench, a series of spaced and circularly arranged supports for suspending a wreath in a horizontal plane above the work bench, an opening in the bench, an annular normally closed shuttle carrying a spool of binding thread mounted to extend through said opening with its axis substantially tangent to a wreath on said supports, a gate to open said shuttle for threading a wreath core and taking a wreath out of winding relation to the shuttle, said supports and shuttle being so arranged with respect to the work bench that a workman at the bench has access to a wreath core on all sides to apply foliage, to intermittently move the core through a complete rotation by hand, and power multiplying means operable by the workman at the bench to rotate said shuttle in relation to the intermittent movements of the core.

6. The combination in an apparatus to bind foliage on a core wire, a workman's bench, an annular shuttle carrying a binding filament, a pair of core wire supports arranged closely ad-

jacent and on opposite sides of the shuttle's winding plane for said filament, said supports extending above the bench for a core wire to rest in horizontal position thereon as it extends through the axis of said shuttle, one of said supports being positioned close to the winding plane so as to have the binding wire applied to such support, said parts being arranged so as to permit the workman to move the core wire at any time and to apply foliage to all sides of such wire and determine at what part of the core wire the binding filament is applied, and means operable by the workman to rotate said shuttle.

7. The combination in a wreath making machine, a workman's bench having an opening through the working surface, a circular strap member supported from the bottom of the bench and extending through said opening, an annular shuttle resting loosely on said strap member for rotatable support, a belt extending around said shuttle so as to drive it like a pulley, driving means for said belt operable by the workman at the bench, supporting means on which a core wire threaded through the axis of said shuttle may be suspended in horizontal position above the work bench with freedom to be moved at any time by the workman, either during the shuttle's rotation to change the position for application of the shuttle's binding thread or for him to apply foliage on all sides of the core wire.

8. The combination in a wreath making machine a workman's bench, pulleys at opposite ends one of which is constructed as an annular shuttle for carrying binding thread or wire, a gate in the shuttle pulley operable to open between the flights of the belt, each pulley having its lower part extending through the bench to locate the lower flight of the belt below the bench and the axis of the shuttle pulley closer to but spaced above the working surface of the bench, means on the bench at the shuttle pulley end to suspend a core wire extending through the axis of the shuttle pulley for winding the binding wire thereon, such suspension permitting the workman to arrange the foliage prepared at the bench, on all sides of the core wire, said core wire being movable solely by the workman, power translating devices operable solely by the workman for driving said shuttle and belt.

9. The combination of claim 8 and means operable by the surface of the pulley not used for the shuttle, to wind binding thread or wire on the shuttle spool.

10. The combination in a wreath making machine an apparatus comprising a workman's bench having a pulley driven winding shuttle, means to guide a wire core into threaded relation to the axis of the shuttle and in suspended condition above the bench for the workman to apply foliage exactly where it is desired to have it bound on the core by the shuttle's rotation, supply spools for core wire and binding filament rotatably mounted under the bench, retaining means to hold the ends of such supply extending from the top of the bench, the core wire in line with the shuttle opening and the building means in line with a shuttle spool winding device, said device comprising a driving pulley having a belt drive to said shuttle and a spool holder normally held out of position between the flights of the driving belt.
